UNITED STATES PATENT OFFICE.

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK.

ALARM DEVICE FOR CLOCKS IN SIGNALING SYSTEMS.

Application filed November 20, 1924. Serial No. 751,059.

The present invention is directed to an improvement in the copending application of Thomas J. Watson, Serial No. 749,641, filed Nov. 13, 1924, and in my copending application, Serial No. 750,033, filed Nov. 15, 1924.

In the Watson application a device is disclosed in which a time designation is made within the apparatus to show the time at which a correlated visual signal failed to function and in my copending application provision is made for making a similar designation when a so-called flashing type of signal fails to function for a sustained time period.

With either of the foregoing systems the clock mechanism itself may stop, in which event the time designation of a signal failure would be erroneous.

The present invention has for its objects the provision of means for sounding, displaying or otherwise calling into operation an alarm device to apprise inspectors and others passing the signal device that the clock mechanism has failed.

A further object of the present invention resides in the provision of means brought into operation by a sustained failure of a visual signal for interrupting the clock operation and in addition means are provided for preventing the resumption of the clock operation if current is reapplied to the line and the visual signal is reestablished. In this way the clock indicating device displays the time of the first failure of a visual signal.

The drawing shows diagrammatically one embodiment of my invention. 10 and 11 are the supply mains which supply current to the signal device 12. This signal device 12 is of the flashing signal type described in my copending application having a thermostat socket 13 to control the flashing of the signal. 14 is a relay coil disposed in main 11 and 15 is the time delayed relay structure which is arranged to keep the control magnet 15^a energized at all times during the normal operation of signal 12 and to open the circuit to magnet 15^a upon a sustained interruption of operation of the flashing signal 12. Upon magnet 15^a becoming deenergized armature 16 is drawn downwardly and retained in position by a catch 17. This armature operation stops the clock escapement de-

vice 18 and thereby designates the time of 65 sustained signal failure on the time tape 18^a. Catch 17 prevents armature 16 being retracted if for any reason the magnet 15^a is again energized. Disk 19 is driven by the clock mechanism and has a plurality of 70 ratchet teeth upon its periphery. Cooperating with these ratchet teeth is a spring contact member 21 which is arranged to either make contact with the top of the teeth or to open a contact if disk 19 stops at an 75 intermediate position. A wire 22 supplies current to disk 19 from supply main 11. Leading from contact 21 is a circuit 23 containing two relay coils 24, 25, and extending back to line 10. Associated with relay coil 70 24 is an armature 26 and associated with coil 25 is an armature 27. Each of the armatures 26 and 27 is provided with a retarding dash pot 28 which respectively delay the armatures 26 and 27. Armature 26 tends to 75 close contacts 30 upon the energization of coil 24 and armature 27 tends to close contacts 31 upon the deenergization of coil 25. So long as the clock driven disk 19 continues its rotation a series of timed current 80 impulses will be sent through relay coils 24 and 25. The duration of these impulses with regular and proper clock operation is such that neither contact 30 nor 31 will be permitted to close. If, on the other hand, 85 the clock slows down or stops entirely one or the other of these contacts 30 or 31 will close. Contacts 30 will close if pawl 21 is in contact with the ratchet 19 with the clock stopped or running slow, and if the clock 90 stops or runs slow with pawl 21 out of contact with the ratchet teeth contacts 31 will eventually close. The closure of one or the other of these pairs of contacts 30 or 31 will establish an alarm circuit 32 and illuminate 95 an alarm visual signal D.

The alarm D may be either a visual or audible alarm but it is here shown as of the visible type. Obviously a bell could be used if desired. I prefer to locate the signal D 100 on the pedestal as shown.

The establishment of the alarm D is adapted to show that the clock-controlled time tell-tale mechanism 18 has stopped or has slowed down to such an extent as to cause 105 the tell-tale device to function improperly.

What I claim is—

1. In a signal system wherein a visual

signal acts as a guide to traffic, a tell-tale mechanism adapted to show signal failure, a control member operated by said mechanism, and means controlled by said member upon the improper functioning of said mechanism for giving an alarm for the purpose described.

2. In a signal system including a visual traffic signal, a clock-controlled tell-tale mechanism with provisions for showing the time of signal failures, an alarm circuit, a clock-controlled member, a contact means controlled thereby, a relay circuit, and a plurality of delayed action relays therein, one of said relays having provisions for establishing the alarm circuit upon a sustained closure of the contact means by the clock-controlled member, the other of said relays having provisions for closing the said alarm circuit upon sustained opening of said contact means because of stoppage or slow action of the clock-controlled member.

3. In a signal system having a clock-controlled tell-tale mechanism adapted to show

the time of signal failures, a clock driven as member, a contact element cooperating therewith to be operated thereby, a relay circuit including said element and member and controlled thereby, an alarm circuit, and delayed action relay means in said relay circuit with provisions for establishing said alarm circuit upon the stoppage or slowing down of the clock driven member.

4. In combination with a clock, a clock-controlled member, contact means controlled thereby, a relay circuit and a plurality of delayed action relays therein, one of said relays having provisions for establishing an alarm circuit upon a sustained closure of said contact means by the clock-controlled member, the other of said relays having provisions for closing said alarm circuit upon sustained opening of said contact means because of stoppage or slow action of the clock-controlled member.

In testimony whereof I hereto affix my signature.

JAMES W. BRYCE.
